UNITED STATES PATENT OFFICE.

WILLIAM H. SUHR, OF OELWEIN, IOWA.

TANK-HEATER.

1,073,544.

Specification of Letters Patent. Patented Sept. 16, 1913.

Application filed April 23, 1913. Serial No. 763,126.

To all whom it may concern:

Be it known that I, WILLIAM H. SUHR, a citizen of the United States, residing at Oelwein, in the county of Fayette and State of Iowa, have invented certain new and useful Improvements in Tank-Heaters, of which the following is a specification, reference being had to the accompanying drawings.

10 This invention relates to improvements in tank heaters such as are commonly employed for heating water in stock watering tanks, the principal object of the invention being to provide a simple and inexpensive device 15 for this purpose whereby the water may be maintained at a uniform temperature and prevented from freezing in cold weather.

Another object of the invention resides in the provision of improved means for directing the fuel into the fire box of the heater, said directing means also serving the purpose of a closure or door for one end of the fire box whereby the heat is conserved.

25 A still further object of the invention is to provide a tank heater of the above character which consists of few parts which are of simple construction and may be inexpensively manufactured to produce a heater 30 which may be retailed at nominal cost and is highly efficient and serviceable in practical use.

With the above and other objects in view as will become apparent as the description 35 proceeds, the invention consists in certain constructions, combinations and arrangements of the parts that I shall hereinafter fully describe and claim.

For a full understanding of the invention, 40 reference is to be had to the following description and accompanying drawings, in which—

Figure 1 is a longitudinal section of a tank heater showing the same arranged in a stock 45 watering tank. Fig. 2 is a section taken on the line 2—2 of Fig. 1. Fig. 3 is a section taken on the line 3—3 of Fig. 1. Fig. 4 is a plan view partly broken away; and Fig. 5 is a detail sectional perspective view.

50 Referring in detail to the drawings, 5 designates the tank which may be of any desired form or construction, and 6 indicates generally my improved heater which is adapted to be arranged therein, the body 55 of the heater being entirely submerged.

My improved heater includes the body 7

which is provided upon its bottom wall with suitable supporting legs 8 preferably arranged at the corners thereof whereby the bottom of the heater is disposed in spaced relation to the base of the water tank. At one of its ends, the body of the heater is vertically extended as shown at 9, and this extension is provided with a hinged top or cover plate 10 having a draft opening 11 60 therin. This draft opening is adapted to be closed by means of a pivotally mounted valve plate 12. The cover 10 is further provided with a suitable handle 13 whereby the same may be moved to its open position 70 when it is desired to feed the fire box of the heater which is indicated by the numeral 14. In this fire box adjacent to the bottom of the heater, a grate 15 is arranged. This grate consists of a longitudinally slotted 75 plate having its ends downwardly flanged as indicated at 16 to provide supports for the intermediate body portion of the plate. One of the flanges 16 has a plurality of openings 17 formed therein and upon this flange, a 80 sliding draft regulating plate 18 is mounted whereby any desired number of the openings may be covered to regulate the entrance of air beneath the grate. 19 designated a movable door or plate which is hingedly mounted 85 as indicated at 20 upon one end of the grate 15. This hingedly mounted door when in its vertical position shown in full lines in Fig. 1, constitutes a closed end wall 90 for one end of the fire box 14 and when disposed at an inclination as shown in dotted lines in said figure, this door serves as a directing means for the fuel which is fed to the heater when the hinged cover plate 10 is raised. The other end of the body 7 of 95 the heater is provided with an opening to which one end of the pipe 21 is connected. Through this pipe the smoke and the products of combustion pass and find an outlet through the vertically disposed stack 22 100 which extends above the tank 5. A butterfly valve 23 is arranged in this stack, and provides the usual damper therefor. The pipe 21 is made up of a plurality of sections which may be coupled together as indicated 105 at 24 in any preferred manner in order to secure a water-tight connection. This pipe is provided with suitable supporting legs 25 which rest upon the base of the water tank.

From the foregoing description, the construction and manner of operation of my improved tank heater will be clearly and

fully understood. As the pipe 21 as well as the body of the heater is submerged in the water contained in the tank, a maximum of heating efficiency is obtained in the use 5 of the device. By regulating the draft to the fire box, the degree of heat therein may be varied so that the water in the tank can be kept at a uniform temperature. It is of course apparent that the form and 10 portions of the several parts of the invention may be variously modified, as may be required by the particular form and construction of the tank in connection with which the device is used. However, in view of the 15 extreme simplicity of the invention, it will be appreciated that the same can be produced at very small manufacturing cost. The device is also highly serviceable, convenient and efficient in practical operation.

20 While I have shown and described the preferred construction and arrangement of the several elements employed, it is obvious that the invention is susceptible of considerable modification in the form, proportion and arrangements thereof without departing from the essential features or sacrificing any of its advantages, as claimed.

Having thus described the invention, what is claimed is:

- 30 1. A tank heater comprising a body having a feed door at one end and provided with legs whereby the body is supported in spaced relation to the base of the water tank, said body being provided with a fire box, a 35 grate plate in said fire box having its opposed ends flanged to space the grate plate from the bottom wall of said body, one of

the flanged ends of the grate plate being fixed to one of the body walls and the other flange of the grate plate being provided 40 with a plurality of openings, a door pivotally mounted upon the latter end of the grate plate and constituting one of the end walls of the fire box when in its closed position, said door being movable to an inclined 45 position and its upper end in contact with one of the end walls of the body, to direct the fuel into the fire box, a smoke outlet pipe connected to the opposite end of the body, and supporting legs for said pipe 50 adapted to rest upon the base of the water tank.

2. A tank heater comprising a body having a feed door at one end, said body being provided with a fire box, a grate plate in 55 said fire box having its opposite ends flanged to space the grate plate from the bottom wall of said body, one of said flanges having openings therein, a sliding plate adjustable over said openings, a door pivotally mounted upon one end of the grate plate and constituting one of the end walls of the fire box when in its closed position, said door being movable to an inclined position with its upper end in contact with one of the end walls 60 of the body to direct the fuel into the fire box, and a smoke outlet pipe connected to the opposite end of the body.

In testimony whereof I hereunto affix my signature in the presence of two witnesses.

WILLIAM H. SUHR.
